(57) CLAIM

The ornamental design for a combined handkerchief and handkerchief holder, as shown and described.

DESCRIPTION

FIG. 1 is a front view of a combined handkerchief and handkerchief holder showing the new design.

FIG. 2 is a back view of the handkerchief holder of the combined handkerchief and handkerchief holder, shown separately from the handkerchief to show aspects of the design that are not visible when combined.

FIG. 3 is a front view of the handkerchief of the combined handkerchief and handkerchief holder, shown separately from the handkerchief holder to show aspects of the design that are not visible when combined.

FIG. 4 is a back view of the combined handkerchief and handkerchief holder; and,

FIG. 5 is a back view of the combined handkerchief and handkerchief holder, shown in an alternate configuration in a closed position.

1 Claim, 5 Drawing Sheets
